by H. H. Willson, Atty.

UNITED STATES PATENT OFFICE.

JACOB SAMUEL COCHRAN, OF SALINA, KANSAS.

AUTOMATIC WAGON-BRAKE.

SPECIFICATION forming part of Letters Patent No. 573,446, dated December 22, 1896.

Application filed March 25, 1895. Serial No. 543,127. (No model.)

To all whom it may concern:

Be it known that I, JACOB SAMUEL COCHRAN, a citizen of the United States, residing at Salina, in the county of Salina and State 5 of Kansas, have invented a new and useful Automatic Wagon-Brake, of which the following is a specification.

My invention relates to an improved automatic wagon-brake in which action is produced through movement of neck-yoke on front end of wagon-tongue in connection with levers as attached with chains, rods of iron, and strap-links of iron; and the objects of my invention are, first, to provide an efficient 10 self-acting wagon-brake, serviceable under all conditions of wagon use—one that is not dependent upon the wagon-body for attachment or operation; second, to provide a wagon-brake appliance that energy of team 15 hitched to the wagon causes self-adjustment in application of the brake; third, to provide an automatic wagon-brake that when wagon-body is in place on the wagon can be either operated by energy of team automatically or 20 in the usual manner with hand-lever and ratchet fixed on side of wagon-body, and that may be operated by the combined energy of both team and operator. I attain these objects by the mechanism illustrated in the accompanying drawings, in which—

Figure 1 is a plan of my automatic wagon-brake as attached to the running-gearing of a farm-wagon. Fig. 2 is a side view of my automatic brake appliance as attached and showing wagon in section with body in place on bolsters. Fig. 3 is an isometrical view of levers situated over rear hounds of wagon, the tongue of wagon and connecting rods and chain over same in Figs. 1 and 2 shown broken 35 to curtail space of drawings.

Similar numbers refer to similar parts in each figure.

The hoop 1 and cross-bar 2 are made of flat bar-iron forming the frame for fixed portion 45 of the appliance, the same being bolted securely to rear hounds of wagon. The wooden lever 3 and flat iron lever 4 are pivoted to cross-bar 2 with iron bolt and bridle-strap 10, said levers being connected to brake-beam 8 50 with short independent chains. The right-hand end of lever 3 is connected to neck-yoke 24 by use of iron rods, strap-links, chain, and

pulley, numbered 6, 14, 16, 17, 22, 23, and 25, respectively. The same end of iron lever 4 can be connected to hand-lever and ratchet 55 on side of wagon-body, when desirable, with iron rod 5, which is to be detached from lever 4 at times of using wagon with my brake without body in place on the wagon. The left-hand end of lever 3 is connected to movable 60 doubletree 21 by iron rod, chain, and strap-link numbered 7, 15, and 20, respectively.

Fore-and-aft movement of doubletree on wagon-tongue is provided by use of a slotted iron plate and open-loop-form bridle 18, admitting movement in line with tongue, and at same time avoiding end motion of doubletree through agency of draw-pin 19, which is formed with T-shaped foot having a slotted hole through same near top end at right angle with T-foot to admit passage for iron strap-link 17 through said draw-pin, which provision admits of introducing the T-foot of draw-pin through slot in plate, (the plate being slightly blocked up from and bolted to the 75 wagon-tongue,) swinging same one-quarter turn on long axis, slipping the doubletree 21, strap-link 20, and bridle 18 over said draw-pin in place and then inserting strap-link 17 through top portion of the draw-pin in combination of the movable doubletree device.

The connecting-rod 22, from near draw-pin 19 to chain passing over neck-yoke, is kept in line over tongue of wagon by use of eyebolts at intervals fixed in top of tongue.

The stop for neck-yoke under tongue of wagon is set back a distance sufficient to permit the required movement of neck-yoke backward on tongue to influence chain 23, which is connected to front side of neck-yoke 90 24 about pulley 25, thereby straining all connections back to and the right-hand end of lever forward, (marked 3.)

Pulley 25 is held in position over near end of tongue by a curved iron clevis 26, formed 95 with a saddle-rest on tongue near neck-yoke and kept in position by bolt through forward arms of clevis and iron loop of wagon-tongue.

After application the position of brake-beam 8 is recovered by force of steel springs 100 11, fastened to said beam and acting against iron stops 12, that are riveted to sides of hoop 1, which admits of flexible connection between beam 8 and the levers 3 and 4, permitting ac-

tion of wagon-brake automatically or by hand-power. Connections of lever-chains to clevis of brake-beam 8 are made with eyebolts having nuts and long screw-thread for neat adjustment of length, and the said beam 8 is held in position endwise on hoop 1 by staples inserted over sides of hoop up into brake-beam.

Connection of chain to wooden lever 3 is made through office of a short shaft 13, having arms, one on each end, bent in opposite directions from center of shaft, the same being fixed in position with journal-bearings against back edge of lever, as most clearly shown in Fig. 3. The right-hand arm of said shaft is flattened with an eyehole receiving the first, a long curved link of chain, and standing upright when wagon-brake is at rest, at same time the arm on reverse end of shaft hanging downright; this provision to hasten the movement of beam 8 and rubbers 9 toward rear wheels of wagon, caused by the downright arm of shaft 13 coming in contact with cross-bar 2 upon the first impulse of automatic brake to act and the consequent rocking of shaft backward, with its upper half and upright arm bringing chain and beam 8 along with said movement under influence of the team in application of the brake.

Connecting-strap 14 passes through mortise in front bolster close to right side of king-bolt. Chain 15 is kept in position where passing front end of coupling-pole by running through a staple in left edge near end of said coupling-pole. A keyhole in strap-link 17, just in rear of draw-pin 19, permits keying the appliance from action at times desirable to back the team and wagon.

In action of my automatic wagon-brake, when the tendency of wagon on a decline of road is to move forward and crowd the team,

the neck-yoke 24 then being influenced backward on tongue of wagon and consequent with attachment of chain passing about pulley 25, and being connected along back to right end 45 of lever 3, which is thus brought forward, setting the brake. At same time, by virtue of reverse movement with opposite end of said lever 3 acting on pivot and the connections therefrom to draw pin 19 with slotted iron 50 plate and loop-bridle 18, the doubletrees 21 are moved backward on tongue of wagon a like distance to reverse movement of opposite end of lever 3. Reflex action of the brake appliance occurs the instant team is required to 55 strain forward on doubletrees, which, by reason of before-mentioned connections, causes reciprocate action of the brake appliance and instant freedom of rubbers 9 from wheels of wagon.

What I do claim as my invention, and desire to secure by Letters Patent, is—

1. In the combination with a wagon-brake, the hoop 1 and cross-bar 2 riveted together and bolted to the rear hounds of a wagon, in 65 the form and for the purpose substantially as described.

2. In the combination with a wagon-brake, the levers 3 and 4 pivoted and bridled with rod and chain connections, to act in conjunction or independently as described and shown. 70

3. In an automatic wagon-brake the combination of a slotted iron bed-plate and loop bridle-strap 18 with a draw-pin 19 for doubletrees having a T-shaped foot and slotted hole 75 through same near top end as and for the purpose substantially as set forth.

JACOB SAMUEL COCHRAN.
